DESIGN FOR A COAT

Max Kolmer, New York, N. Y.

Application December 2, 1935, Serial No. 59,877

Term of patent 3½ years

To all whom it may concern:

Be it known that I, Max Kolmer, a citizen of the United States of America, residing in Borough of Manhattan, city, county, and State of New York, have invented a new, original, and ornamental Design for a Coat, of which the following is a specification, reference being had to the accompanying drawing, forming part thereof.

I claim:

The ornamental design for a coat substantially as shown.

MAX KOLMER.
